(57) **CLAIM**

The ornamental design for a wood fence panel, as shown and described.

DESCRIPTION

FIG. 1 is a perspective view of a wood fence panel showing my new design;

FIG. 2 is a front elevational view thereof;

FIG. 3 is a rear elevational view thereof;

FIG. 4 is a right side elevational view with the left side being a mirror image thereof;

FIG. 5 is a top view thereof; and,

FIG. 6 is a bottom view thereof.

The broken line showing of the post in FIGS. 1–6 and the rear support in FIG. 3 is for illustrative purposes only and forms no part of the claimed design. The bracket and ghost line connection is intended to show indefinite length.
